UNITED STATES PATENT OFFICE.

HENRY LUTZENKIRCHEN, OF HARTFORD, CONNECTICUT, ASSIGNOR OF
ONE-HALF TO CAMILLO L. FISCHER, OF SAME PLACE.

CAR-FENDER.

SPECIFICATION forming part of Letters Patent No. 658,854, dated October 2, 1900.

Application filed February 14, 1900. Serial No. 5,137. (No model.)

To all whom it may concern:

Be it known that I, HENRY LUTZENKIRCHEN, a citizen of the United States, residing at Hartford, in the county of Hartford and State of Connecticut, have invented certain new and useful Improvements in Car-Fenders, of which the following is a specification.

This invention relates to a fender which has a part that is automatically thrust forward when necessary to catch and retain a body in its path.

The object of this invention is to provide a simple fender which is so constructed that the movable part will not be thrust forward unless a body falls upon the fender.

The novel feature of the fender which embodies this invention is the locking arrangement which restrains the movable part in such manner that it is only released by weight upon the fender, so that the mere hitting of an obstruction, as a stone or a collision with another vehicle, does not cause the fender to operate, but the projecting of a body onto the fender causes it to so act that the body cannot roll off in front.

Figure 1 of the accompanying drawings shows a side view of a fender that embodies the invention. Fig. 2 shows a plan of the fender. Fig. 3 is an enlarged sectional view showing the lock which holds the movable part until weight is brought upon the fender. Fig. 4 is a detail showing the connection between the supporting-arms and the frame, and Fig. 5 is a detail showing the method of connecting the rods with the striking bar of the fender.

The arms 1 are adapted to be fixed to the end of the car-platform, and the side bars 2 of the frame are pivotally connected with these arms by a rod 3. These bars curve downwardly and forwardly and at the front end are joined by a bar 4. The exact position of the lower end of the frame is adjusted by means of the set-bolts 5, that turn in lugs 6, extending backward from the upper ends of the side bars of the frame, which bolts against the under edges of the fixed arms.

A tube 7 is hinged to the pivot-rod 3 near each side of the frame, and between these tubes 7 a number of smaller tubes 8 are hinged to the rod. These tubes are joined at the

lower ends by a bar 9 and are curved substantially the same as the side bars of the frame. Springs 10 are secured to the frame-bar 4 near each side, so as to press upwardly 55 against the tubes 7 and hold up the lower ends of the tubes and the bar 9 with a yielding pressure. The upward movement of the tubes is limited by lugs 11, extending from the side bars 2 of the frame. 60

Movable in the tubes 7 are rods 12, and movable in the smaller tubes 8 are rods 13. These rods, which curve the same as the tubes, are fastened to the bar 14, that extends across the front of the frame. In the large 65 tubes 7, back of the ends of the rods 12, springs 15 are arranged to thrust the rods outwardly.

Fixed to and extending rearwardly from the middle of the tube-bar 14 is a hook 16. 70 Fixed to and extending forwardly from the frame-bar 4 is a hook 17. The shoulders of these hooks so engage when the outer ends of the tubes are held raised by the springs 10 that the rods cannot be forced forwardly 75 out of the tubes by the springs 15.

Under ordinary circumstances the springs 10, attached to the front bar of the frame, thrusting upwardly against the side tubes 7, hold the front end of the hinged tubular portion of the frame up against the lugs 11. With the front end of the hinged tubular part of the frame held raised the hook attached to the fixed frame-bar engages and holds the hook attached to the movable or 85 striking bar in such manner that the springs, which are compressed in the larger tubes, cannot throw the rods and striking-bar forwardly. Any backward blow or pressure upon the bar 14, as striking a timber or stone or 90 collision with a vehicle or hitting a body that is at once thrown to one side, will not cause the hooks to be disengaged. However, should the body of a person or any other animal or any obstruction be struck and precipitated 95 upon the fender and the weight of the object come upon the hinged tubular frame, which is by the springs held slightly above the fixed frame, that weight will so depress the front end of the tubular frame that the hook on 100 the striking-bar will be forced down away from the fixed hook on the frame-bar, releas-

ing the striking-bar and allowing the springs to throw forwardly the movable part of the fender. The tubes are so shaped that when the striking-bar and its rods are thrown forward they curve upwardly in such manner that they will hold the object picked up.

By means of this simple construction a fender is provided that will ordinarily project but a short distance in front of a car and one that will not be released to pick up a body unless the body is thrown so as to fall in front of the car upon the fender.

I claim as my invention—

1. A fender having a frame adapted to be fixed to a car, a frame hinged to the fixed frame and adapted to be depressed by weight brought upon it, a frame movably supported by the hinged frame, springs tending to thrust the movable frame forwardly from the hinged frame, and a lock arranged to hold the movable frame with the springs compressed until the hinged frame is depressed, substantially as specified.

2. A fender having a frame adapted to be fixed to a car, a frame hinged to the fixed frame and adapted to be depressed by weight brought upon it, a frame movably supported by the hinged frame, springs tending to thrust the movable frame forwardly from the hinged frame, a hook extending from the fixed frame, and a hook extending from the movable frame in such manner that they normally engage and hold the movable frame with the springs compressed until the hinged frame is depressed, substantially as specified.

3. A fender having a frame adapted to be fixed to a car, a tubular frame hinged to the fixed frame and adapted to be depressed by weight upon it, rods movably supported by the tubular frame, a striking-bar secured to the outer ends of the rods, springs located in tubes tending to thrust the rods and striking-bar forwardly from the tubular frame, and a lock arranged to hold the striking-bar and

rods with the springs compressed until the tubes are depressed, substantially as specified.

4. A fender having a frame adapted to be fixed to a car, a tube hinged to the fixed frame near each side, tubes hinged to the fixed frame between the side tubes, a bar connecting the outer ends of the tubes, rods extending into the tubes, a striking-bar connecting the outer ends of the rods, springs in the side tubes tending to thrust the rods and striking-bar forwardly from the tubes, and a lock arranged to hold the striking-bar and the rods with the springs compressed until the tubes are depressed, substantially as specified.

5. A fender having a frame adapted to be fixed to a car, a tube hinged to the fixed frame near each side, tubes hinged to the fixed frame between the side tubes, a bar connecting the outer ends of the tubes, springs lifting the outer ends of the tubes and the tube-bar, rods extending into the tubes, a striking-bar connecting the outer ends of the rods, springs in tubes tending to thrust the rods and striking-bar forwardly from the tubes, and a lock arranged to hold the striking-bar and rods with the springs compressed until the tubes are depressed, substantially as specified.

6. A fender having a frame adapted to be fixed to a car, a frame hinged to the fixed frame, a frame movably supported by the hinged frame, springs tending to thrust the movable frame forwardly from the hinged frame, springs tending to lift the hinged frame and the movable frame, and a lock holding the movable frame when the hinged frame is raised and releasing the movable frame when the hinged frame is depressed, substantially as specified.
